Fig. 10

FIG. 1 is a perspective view of a text editing terminal embodying our inventive design taken from the upper left-hand corner of the front;

FIG. 2 is a side view thereof;

FIG. 3 is a front view thereof;

FIG. 4 is a side view thereof, opposite that shown in FIG. 2;

FIG. 5 is a rear view thereof;

FIG. 6 is a top view thereof;

FIG. 7 is a perspective view of a second embodiment of a text editing terminal embodying our inventive design taken from the upper left-hand corner of the front;

FIG. 8 is a front view thereof;

FIG. 9 is a top view thereof; and

FIG. 10 is a rear view thereof.

The side views of the terminal of FIG. 7 are substantially identical to the side views of the terminal of FIG. 1.

We claim:

The ornamental design for a text editing terminal, as shown and described.
